Primary Examiner — Karen S Acker*Assistant Examiner* — Steven B Reinholdt, Jr.(74) *Attorney, Agent, or Firm* — Cramer Patent & Design, PLLC; Aaron R. Cramer(57) **CLAIM**

The ornamental design for a perforated stir stick, as shown and described.

DESCRIPTION

FIG. 1 is a perspective top front right view of a perforated stir stick, showing my new design;

FIG. 2 is a perspective top rear left view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is an enlarged top plan view thereof; and,

FIG. 8 is an enlarged bottom plan view thereof.

The text drawn in broken line illustrates portions of the perforated stir stick that form no part of the claimed design.

1 Claim, 8 Drawing Sheets(56)
